UNITED STATES PATENT OFFICE.

DANIEL WILLETS, OF BROOKLYN, NEW YORK.

DESIGN FOR A VEGETABLE-DISH.

SPECIFICATION forming part of Design No. 13,995, dated June 19, 1883.

Application filed April 18, 1883. Term of patent 3½ years.

To all whom it may concern:

Be it known that I, DANIEL WILLETS, of Brooklyn, in the county of Kings and State of New York, have invented and produced a new 5 and original Design for Vegetable-Dishes and other Table-Ware, of which the following is a full, clear, and exact description.

Reference is to be had to the accompanying drawings, forming part of this specification, in 10 which similar letters of reference indicate corresponding parts in both the figures.

Figure 1 is a perspective view of a dish made according to my new design. Fig. 2 is a plan view of the same.

15 The dish A, which is made quadrilateral, with sides of equal or unequal length, has all its sides bulged outward or made segmental, so that the plan view of the dish will be a quadrilateral figure having its opposite segmental 20 sides convexed outwardly, as shown. The ends of the segmental lines are united by curves. Each side of the dish is composed of a top vertical part, B, terminating in a curved part, C, which extends outward from the bottom of

the straight part B, and is then gently curved 25 inward, as shown. The base D can be made straight or inclined outward. A small head, a, is formed at the upper edge of the straight part B.

Soup-tureens, tea-pots, sugar-bowls, &c., can 30 be made according to my new design.

I claim—

1. The design for a quadrilateral vegetable-dish, having sides formed of a vertical outwardly-convex top part, B, and a curved part, 35 C, below the convex top part, B, as herein shown and described.

2. The design for a quadrilateral vegetable-dish, having sides formed of a vertical outwardly-convex top part, B, having a bead at 40 its upper edge, and a curved part, C, below the convex top part, B, as herein shown and described.

DAN. WILLETS.
